UNITED STATES PATENT OFFICE.

ARTHUR M. FERGUSON, OF BURLINGTON, KANSAS, ASSIGNOR TO GOLD MEDAL CAMP FURNITURE MANUFACTURING CO., OF RACINE, WISCONSIN, A CORPORATION OF WISCONSIN.

FOLDING COT.

1,170,229.

Specification of Letters Patent.

Patented Feb. 1, 1916.

Application filed December 23, 1912. Serial No. 738,187.

To all whom it may concern:

Be it known that I, ARTHUR M. FERGUSON, a citizen of the United States, residing at Burlington, in the county of Coffey and 5 State of Kansas, have invented certain new and useful Improvements in Folding Cots, of which the following is a specification, reference being had to the accompanying drawing, forming a part thereof.

10 This invention relates more particularly to folding camp beds or cots having side rails each composed of two sections pivotally connected with each other and three pairs of folding legs. 15 Its main objects are to enable such beds or cots to be folded into shorter compass without increasing the number of legs, and at the same time to provide for their extension when unfolded to the ordinary or stand- 20 ard length.

It consists in the construction, arrangement and combination of parts, as herein-after particularly described and pointed out in the appended claims.

25 In the accompanying drawing like characters designate the same parts in the several figures.

Figure 1 is a plan view of a folding or collapsible cot embodying the invention, the cot 30 being unfolded and set up; Fig. 2 is a side elevation of the same; Fig. 3 is an end elevation on an enlarged scale as viewed from the left relative to Figs. 1 and 2, the fabric, cover or top being omitted and the cross 35 bar indicated by dotted lines; Fig. 4 is an enlarged elevation showing one side of the folding end-extension and associated parts of the frame unfolded; and Fig. 5 is a similar view showing the same parts folded.

40 As shown in Figs. 1, 2 and 3, the cot comprises folding side rails each composed of two main sections *a*, connected at their inner ends by hinge joints and three pairs of folding legs *b* and *c*, connected at their upper ends by hinge joints with the side rails, one pair at or adjacent to the inner ends of 45 said sections, and two pairs at the outer ends thereof. The legs *b* and *c* of each pair are preferably crossed and pivotally connected 50 with each other at or near the middle, as shown in Figs. 3 and 5, by S-shaped or reversely bent metal plates *d*, riveted or otherwise fastened to opposite sides of adjacent 55 ends of the sections of the legs *c* and by rivets or pins *e* secured at the ends in said

plates and passing loosely through the intervening legs *b*. This connection permits the legs of each pair to be folded snugly against and parallel with each other, and limits their unfolding by the abutment of the inner 60 ends of the sections of legs *c* against opposite sides of the legs *b*.

The end legs are connected with the side rails by L-shaped metal plates *f* and *f'*, which are riveted or otherwise fastened to 65 opposite sides of the legs in planes parallel with said rails, and extend beyond the adjacent ends of the legs and laterally therefrom toward adjacent ends of the rails, and are pivotally fastened to the side rails by rivets 70 or pins *g* secured at their ends in the offset ends of the plates and passing loosely through the intervening rail sections.

The legs of the middle pair are hinged to the inner ends of the rail sections *a* by T-shaped metal plates *h*, the middle limbs of 75 which are riveted or otherwise fastened to opposite sides of the legs and the cross limbs of which are parallel with the extended side rails and are pivotally fastened thereto by 80 rivets or pins *i* secured at their ends in said plates, and passing loosely through the interposed rail sections.

The folding cot frame as thus far described, is of a well known construction and 85 design except that the rail sections are shorter, and the offset limbs of the hinge plates *f'* are longer and broader to permit the folding of the end extension between the side rails and adjacent end legs and to brace 90 and stay said extension when unfolded, as hereinafter explained, and no claim thereto *per se* is herein made. To permit the shortening of the rail sections so that the cot may 95 be folded into a shorter length and placed in a case or chest of a prescribed length in accordance with present United States Army regulations, without increasing the number of legs, and at the same time to make the cot when unfolded and set up, of the required or desired length, it is provided with a folding end extension comprising side bars *j* and a detachable or removable cross bar *k*. The side bars *j* are hinged at their inner 100 ends to rail sections *a* on the upper sides thereof, and at a distance from their outer ends by L-shaped metal plates *l*, which are riveted or otherwise fastened to the rail sections on the same sides thereof as the plates *f'*, and are pivotally fastened to the side ex- 105 110

tension bars *j* by rivets or pins *m*, secured at their ends in the upwardly projecting limbs of said plates and passing loosely through said bars, as shown in Figs. 4 and 5, as well 5 as in the other figures of the drawing.

The offset limbs or arms of the hinge plates *l* in which the rivets or pins *m* are secured, are of such a length that the bars *j* when unfolded as shown in Fig. 4, or when 10 folded as shown in Fig. 5, will lie against or close to and parallel with the rail sections *a* along the upper sides thereof. The offset limbs or arms of the hinge plates *f'* in which the rivets or pins *g* are secured, are 15 of such length that the legs to which said plates are attached will fold as shown in Fig. 5, over and parallel with the folded bars *j*, which when the cot is folded, lie between said legs and the rail sections *a*. 20 The plates *f'* and *l* are preferably flanged to embrace opposite sides of the legs and rail sections to which they are rigidly fastened, as shown in Figs. 1, 2 and 3. The plates *f'* are made to project above the 25 upper sides of the rail sections *a* to receive between them and to stay the bars *j* when the cot is unfolded, as shown in Fig. 4, the upper ends of the legs to which said plates are attached then abutting against the 30 under sides of said rail sections. The outer ends of the folding bars *j* are formed or provided with tenons *n*, which fit into sockets in one of the removable cross bars *k* with which the cot is provided, to brace 35 and hold them and the side rails apart when the cot is unfolded.

The flexible fabric top or cover *o*, with which the cot is provided is fastened along the sides to the rail sections *a* and bars *j* 40 and at the ends to the cross bars *k*, by open hems as shown, or by other suitable means.

To fold the cot, the cross bars *k* are removed from the rail sections *a* and extension bars *j* at the ends of the cot and with- 45 drawn from the end hems of the top or cover *o*, and the side rails and extension bars are brought together side by side, thereby folding the several pairs of legs *b* and *c* on their pivot connections *e* with each other, 50 the top or cover *o* being drawn up from between the side rails and extension bars and folded longitudinally along the center. The extension bars *j* are then folded back 55 upon the rail sections *a*, to which they are hinged, and the adjacent pair of end legs is turned up and folded over the extension

bars, as shown in Fig. 5. The other pair of end legs is turned up and folded upon the other rail sections *a*, the offset limbs or arms of the hinge plates *f* in which the pins *g* 60 are secured, being of such length that said legs will fold flat upon and close to said rail sections. The rail sections *a* are then folded on their pivots *i* against opposite sides of the middle pair of legs, the fabric top or 65 cover *o* wrapped about the folded parts, the cross pieces assembled therewith, and the whole bound together in compact form by straps or the like (not shown) with which such cots are ordinarily provided. Obviously, the order of the operations above 70 enumerated may be somewhat varied. The cot is unfolded and set up by a reversal of the manipulations as above explained.

Various modifications in the minor details 75 of construction and arrangement of parts of the cot may be made within the scope of the invention as defined in the following claims.

I claim:

1. A folding bed or cot comprising side rails and folding end legs hinged to the side rails and adapted to fold over the tops of said rails parallel therewith and at a distance therefrom, folding extension bars 80 hinged at one end to the upper sides of said rails at a distance from their outer ends and adapted to be folded between and parallel with said rails and legs and to be unfolded upon and parallel with said rails 85 beyond which they extend when unfolded.

2. A folding bed or cot comprising side rails and folding legs, folding extension bars hinged at their inner ends to the upper 90 sides of said rails at a distance from their ends, and offset hinge plates connecting the legs with said rails and projecting, when the legs are unfolded, above the rails to embrace and stay the unfolded extension bars, the folded legs being adapted to be 100 folded over the tops of said rails parallel therewith and at a distance therefrom, and the extension bars being adapted to fold between and parallel with said rails and legs and to unfold upon, parallel with and 105 beyond said rails.

In witness whereof I hereto affix my signature in presence of two witnesses.

ARTHUR M. FERGUSON.
